UNITED STATES PATENT OFFICE.

WALTER S. MUMMERY, OF MINOT, NORTH DAKOTA, ASSIGNOR OF ONE-HALF TO
ARNE AMUNDSON, OF MINOT, NORTH DAKOTA.

HYDROCARBON-BURNER.

1,120,327.

Specification of Letters Patent.

Patented Dec. 8, 1914.

Application filed May 1, 1913. Serial No. 764,852.

To all whom it may concern:

Be it known that I, WALTER S. MUMMERY, a citizen of the United States, residing at Minot, in the county of Ward and State of North Dakota, have invented certain new and useful Improvements in Hydrocarbon-Burners, of which the following is a specification, reference being had thereto in to the accompanying drawing.

This invention relates to hydro-carbon burners and has for its object the production of a simple and efficient burner wherein an efficient combustion may be produced so as to cause a uniform heat to be created by the flames from the burner.

Another object of this invention is the production of a simple and efficient means for feeding the water to the boiler and keeping the water at a uniform height.

With these and other objects in view, this invention consists of certain novel constructions, combinations and arrangements of parts, as will be hereinafter fully described and claimed.

This invention is illustrated in the accompanying drawings, wherein:—

Figure 1 is a fragmentary side elevation of the burner showing the water supply tank in section. Fig. 2 is a top plan view with one of the baffle plates partly broken away of the burner and the secondary baffle plate removed. Fig. 3 is a section taken on line 3—3 of Fig. 1. Fig. 4 is a section taken on line 4—4 of Fig. 3. Fig. 5 is a detail perspective of the supporting member for the water supply tank. Fig. 6 is a detail perspective of the heat pipes through which the water is adapted to pass. Fig. 7 is a perspective view of the boiler used in connection with the present device. Fig. 8 is a detail transverse sectional view showing the relative arrangement of the steam supply and burner. Fig. 9 is a perspective view of the discharge nozzle used in connection with the present invention.

By referring to the drawings, it will be seen that 1 designates the tray or pan which is provided with a flange 2 extending entirely around the same. This tray or pan 1 is provided with apertures 3 formed in the sides thereof for facilitating the passage of air into the tray or pan and cause an efficient draft therethrough. An asbestos plate 4 is placed in the bottom of the tray or pan 1 and is adapted to be saturated with oil

when the burner is first lighted so as to efficiently heat the boiler 5 prior to the generation of the steam. It, of course, should be understood that the steam will soon be created within the boiler after the oil in the bottom of the pan has been lighted and the flame will burn from the burner pipe in the manner to be hereinafter described.

The boiler 5 is preferably formed of a rectangular body being set upon one of the flanges 2 as illustrated in Fig. 3. This boiler 5 is provided with an inlet pipe 8 which pipe is connected to the water supply tray 9. The boiler 5 is also provided with a discharge outlet 10 which discharge outlet is provided at one end with an overhanging flange 11 adapted to be engaged by the closure cap 12. A pivoted link member 13 is secured to the top of the tank 5 and is adapted to engage the upper face of the cap 12 to hold the same firmly over the outlet aperture 10. The cap 12 is provided with a discharge pipe 14 to which is connected the stub pipe 15 for conveying the steam from the boiler into the several pipes of the burner.

The pipe 15 supports a steam super-heating pipe 16 and this steam super-heating pipe 16 is connected to a parallel super-heating pipe 17 by means of a transversely extending connecting pipe 18, the pipe 18 being connected to the pipes 16 and 17 at their rear ends, or, in other words, at the end opposite to the pipe 15. The parallel super-heating pipe 17 is in turn connected to a secondary super-heating pipe 19 by means of a diagonally extending pipe 20. The pipe 19 carries a plurality of upwardly extending supporting rods 21 and upon these supporting rods 21 is mounted a flame distributing plate 22, the rods 21 passing through the apertures 23 formed in the plate 22. Flame distributing apertures 24 are formed in the plate 22 and are adapted to distribute the flame throughout the entire length of the plate so as to produce an even heating surface. A secondary baffle plate 25 is supported upon the pipes 19 and 17 in the manner as illustrated in Fig. 3 so as to allow the flame from the burner to be distributed over the super-heating pipes 16 and 17 to produce an efficient combustion.

The pipe 19 is provided with a downwardly extending discharge pipe 26 which carries a discharge nozzle or cap 27 over

which nozzle is placed the burner pipe 28. This burner pipe 28 is provided with a plurality of apertures 29 which are arranged in parallel rows for causing the blaze to be discharged in the path of the pipes 16, 17 and 19, as shown in Fig. 8. The burner pipe 28 is secured over the cap 27 by means of the slot 30 fitting over the pin 31 and in this manner may be easily detached from the cap so as to be cleaned if it be so desired. It should be further understood that the pipe 15 is readily detached from the stub pipe 14, thereby also allowing access to be had to the interior of the boiler 5 for the purpose of removing sediment or other accumulation which may be settled in the boiler.

The boiler 5 is provided at one end with a pipe supporting bracket 31' adapted to engage the super-heating pipe 16 at its far end so as to support the same and relieve considerable of the strain from the pipe 15. A plurality of spaced brackets 32 are also mounted upon the tray 1 along the edge thereof and engage the pipe 19 to constitute an efficient support to hold the burner pipe 28 above the floor or base of the tray or pan 1 to allow a free circulation of air under the pan.

It should be understood that the present device may be placed in a desired position within the stove to accomplish the desired purpose. An oil supply pipe 33 is connected to the pipe 19 at its far end and this pipe carries a needle valve 34 for controlling the passage of oil therethrough, the oil passing into the pipe 19 through the aperture 35 formed in the outer end of the pipe.

As above stated, a water supply tank 36 is employed in connection with the present invention, this supply tank 36 being suspended from a standard 37 mounted upon the water supply tray 9. This water supply tray 9 carries a sleeve 38 upon one side which constitutes a socket for receiving the standard 37. This standard 37 is provided with an overhanging end 39 in which is adjustably mounted a supporting hook 40, said supporting hook carrying an adjusting nut 41 for regulating the height of the hook 40 upon the overhanging end 39. The tank 36 is suspended upon the hook by means of a bail 42 and this tank is also provided with a supply opening 43 which opening is normally closed by means of the plug 44. The tank 36 is also provided with a valve casing 45 at its lower end in which works a valve 46 normally held in a closed position by means of a spring 47. The bottom of the tank 36 is held in alinement with the tray 9 by means of guiding brackets 48 which guiding brackets engage the sides of the tank and prevent the lateral movement of the tank relative to the tray 9. If it is desired to allow considerable water to pass through the system, the supporting hook

40 may be adjusted so as to allow the tank 36 to descend upon the tray 9 so as to hold the valve 46 widely open. If only a small quantity of water is desired to flow through the system, the supporting hook 40 may be so adjusted as to hold the valve 46 in a closer arrangement with the valve seat and allow only a small amount of water to pass therethrough.

The cap 27 is provided with an aperture 49 which will allow the oil, before lighting the burner, to pass through the pipe 19, through the pipe 26, and be discharged out through the aperture 49 into the bottom of the pan 1 whereupon the oil will saturate the asbestos plate 4 and by applying a match thereto the oil will become ignited and the heat will generate steam within the boiler 5. The steam will then pass up through the pipe 15, through the pipes 16, 18 and 17, through the pipe 20, through the pipe 19 mixing with the oil passing therethrough, and vaporize the same by reason of the heat and thereby produce carbon which takes up the oxygen of the water and separates the oxygen from the hydrogen and passes down into the tube 26, the cap 27, and thence coming out through the perforations 29 formed in the burner pipe 28, producing an efficient combustion. The flames will then strike the baffle plate 25 and be distributed well over the pipes 16 and 17 and will also be distributed against the plate 22 and in turn passing through the apertures 24 formed therein.

The pan or tray 1 is adapted to fill the entire space in the stove, shutting out any chance for the air passing up by the sides of the flanges 2, thereby causing all of the air to pass through the apertures or perforations 3 in the pan to produce an efficient upward current of air through the burner.

It will be seen by carefully considering Fig. 1 that the tank 36 is larger than the receiving pan 9 and the side edges of this tank 36 overhang the side edges of the receiving pan 9 so as to prevent the dust or dirt which might accumulate upon the outside of the tank 36 from dropping into the pan 9 and causing a sediment to be deposited thereon.

Having thus described the invention, what is claimed as new, is:—

1. A burner of the class described comprising a tray, a boiler carried upon said tray, a plurality of parallel superheating pipes supported above said boiler and connected thereto, a secondary superheating pipe supported to one side of said boiler and connected to the first-named superheating pipes, means for supplying liquid fuel to the secondary superheating pipe, a burner pipe suspended below said secondary super-heating pipe and connected thereto, a plurality of upwardly extending standards 120

carried by said secondary super-heating pipe, a flame distributing plate carried by said upwardly extending rods, and a baffle plate carried by one of the first mentioned 5 super-heating pipes and said secondary superheating pipe.

2. A burner of the class described comprising a tray, a tank, a super-heating pipe carried thereby, a burner pipe carried 10 thereby, said tank provided with a discharge opening, a closure cap fitting over said opening and communicating with said super-heating pipe, said tank provided with an overhanging flange engaging said cap, a 15 latch engaging said cap and normally holding the same upon said boiler and facilitating the removal of said cap for allowing access to be had to the interior of said boiler.

20 3. A burner of the class described comprising a tray provided with flanges, a boiler positioned upon one of said flanges of said tray, a plurality of connected super-heating pipes supported above and connected to said boiler in a plane parallel to the upper face of said boiler, a secondary super-heating pipe positioned to one side of said boiler and connected to one of said first mentioned super-heating pipes, a burner 25 pipe suspended below said secondary super-heating pipe and connected thereto, a baffle

plate supported upon one of said first mentioned super-heating pipes and said secondary super-heating pipe, supporting rods carried by one of said pipes, and a perforated 35 flame distributing plate supported upon said rods for evenly distributing the flame from said burner pipe.

4. An oil burner comprising a tray, a water heater carried thereby, superheating 40 pipes through which steam circulates from the heater, said pipes terminating in a discharge nozzle provided with a pin, a burner provided with fuel discharge outlets and a slot that interlocks with said pin, and means 45 for supplying fuel to one of said superheating pipes.

5. An oil burner comprising a tray, a water heater carried thereby, superheating pipes through which the steam from the 50 heater circulates, a discharge nozzle for the pipes, a burner carried by the nozzle, means for supplying fuel to one of said superheating pipes, a baffle plate resting on the pipes, and a flame distributor plate supported by 55 one of the pipes above the baffle plate.

In testimony whereof I hereunto affix my signature in presence of two witnesses.

WALTER S. MUMMERY.
